UNITED STATES PATENT OFFICE.

ERNEST H. ROSS, OF IOWA CITY, IOWA.

DESIGN FOR A GIRDLE.

Application filed September 27, 1924. Serial No. 10,911. Term of patent 7 years.

To all whom it may concern:

Be it known that I, ERNEST H. Ross, a citizen of the United States, residing at Iowa City, in the county of Johnson and State of Iowa, have invented a new, original, and ornamental Design for Girdles, of which the following is a specification, reference being had to the accompanying drawing, forming part thereof.

The figure is a plan view of a girdle showing my new design.

I claim:

The ornamental design for a girdle, as shown.

ERNEST H. ROSS.
